UNITED STATES PATENT OFFICE.

EDWARD MARSH, OF WASHINGTON, DISTRICT OF COLUMBIA.

TOY BUCKET.

1,352,463.

Specification of Letters Patent. Patented Sept. 14, 1920.

Application filed August 16, 1919. Serial No. 317,987.

To all whom it may concern:

Be it known that I, EDWARD MARSH, a citizen of the United States of America, residing at Washington, in the District of Columbia, have invented new and useful Improvements in Toy Buckets, of which the following is a specification.

This invention relates to a toy bucket and has for its primary object the construction of an article capable of performing two functions, that of carrying sand, and creating a rattling effect.

An object of the invention is to provide a toy bucket having a sand compartment and a noise producing compartment separated from the sand compartment.

Besides the above my invention is distinguished in the use of a false bottom spaced from the main bottom of the bucket to confine in place rattling elements, which strike against the walls of the bucket and against the false bottom to produce a noise.

With these and other objects in view the invention will be better understood from the following detailed description taken in connection with the accompanying drawing: wherein:

The view is a vertical sectional view of my improved bucket in one of its forms.

The bucket 1, of the usual construction,

and having a bottom 2 and a handle 3, has arranged therein at a point spaced from bottom 2, a false bottom 4 that may be secured to the bucket in any suitable manner, 35 such as by solder as indicated at 5. By this arrangement it will be seen that the interior of the bucket is divided into a lower compartment 6 and an upper compartment 7 for the reception of sand or gravel, as 40 my bucket is designed primarily for use at the sea-shore. Arranged in the compartment 6 are rattling elements 8, shown in this particular instance as metallic balls, which in the shaking of the bucket strike 45 upon the false bottom and wall of the bucket to create a noise.

It is of course to be understood that the rattling device may be attached to the bucket in various other manners and therefore I do not desire to be limited in any manner except as set forth in the claim hereunto appended.

What I claim is:

A toy bucket comprising a tapering body 55 portion, a false bottom forced into the body and secured at a predetermined spaced point from the bottom of the body, and balls arranged in the space under the false bottom.

In testimony whereof I affix my signature. 60

EDWARD MARSH.
